(57) **CLAIM**

The ornamental design for a lid for a beverage maker as shown and described.

DESCRIPTION

FIG. 1 is a top, rear perspective view of a lid for a beverage maker showing our new design in a condition of use;

FIG. 2 is a front view of a lid for a beverage maker showing our new design with the container portion removed for clarity purposes;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a top, rear perspective view thereof; and,

FIG. 9 is a bottom, rear perspective view thereof.

The broken lines shown in FIG. 1 depict environmental structure that form no part of the claimed design. The broken lines shown in FIGS. 2-9 depict portions of the lid for a beverage maker that form no part of the claimed design.
